UNITED STATES PATENT OFFICE.

VERNON W. BALZER AND JOHN MCK. BALLOU, OF LOS ANGELES, CALIFORNIA,
ASSIGNORS TO IVAR L. SHOGREN, OF LOS ANGELES, CALIFORNIA.

ELECTRIC FLASHING DEVICE.

Application filed September 14, 1920. Serial No. 410,301.

To all whom it may concern:

Be it known that we, VERNON W. BALZER and JOHN MCK. BALLOU, citizens of the United States, residing at Los Angeles, in the county of Los Angeles and State of California, have invented a new and useful Electric Flashing Device, of which the following is a specification.

This invention relates to devices for automatically and periodically interrupting an electric circuit.

One of the objects of this invention is to provide two independent circuits within the device operatively influencing one another.

Another object is to provide a main operating circuit and a derived circuit, both partly passing through parts of the device.

Another object is to provide a main operating circuit and a derived circuit, both passing through parts of the device, and both influenced by the same source of supply.

Another object is to provide a circuit interrupting means within the device influencing both circuits.

Another object is to provide a circuit interrupting means within the device influencing both circuits, the moment of commencing interruption in the operating circuit being the moment of ending the interruption in the derived circuit, and the moment of ending interruption in the operating circuit being the moment of commencing interruption in the derived circuit.

Another object is to retard the periods between forming a circuit and interrupting the circuit in the operating circuit so as to form desired periods of flashing in the derived circuit.

Another object is to provide adjustable means for adjusting the periods between the flashing and for adjusting the quickness of interruption.

Other objects will appear from the following description and appended claims as well as from the accompanying drawing, in which—

Fig. 1 is a front elevation of the device, the controlling cylinder being illustrated in vertical midsection, and the wiring or circuits being illustrated diagrammatically.

Fig. 2 is a top plan view of the controlling disc valve, illustrating the adjusting means in the face of the disc valve.

The coil 3 and the core 4 form the mag-

netic source of this device when under the influence of the electric source indicated at 5.

As illustrated in Fig. 1, the current from the main electric source 5 passes through the conductor 6, the conductor 7, the coil 3, the conductor 8, the base plate 9, the contact-arm 10, the contacts points 11 and 12, the base or supporting plate 13, and the conductor 14 back to the main electric source 5.

This circuit so formed will hereafter be called the operating circuit.

Another circuit is formed, originating from the same main electric source 5, passing through the conductor 6, the supporting member 15, the spring member 16, the contact points 17 and 18, the contact arm 19, the supporting member 20, the conductor 21, the members and points and means of using current 22, and the conductor 23 back to the main electric source 5.

This circuit will hereafter be called the derived circuit.

Through a closed operating circuit, as shown in the drawing in Fig. 1, the coil 3 causes a magnetizing of the core 4, whereby the block 24 is drawn towards the end 25 of the core and the block or member 26 is drawn towards the end 27 of the core 4, as will easily be understood.

The block 24 being located on the arm 28, pivotally supported as indicated at 29 on the supporting member 30, naturally causes the hammer or member 31 to drop on the spring member 16, thereby interrupting the derived circuit between the contact points 17 and 18, which is normally a quick movement or action.

The block or member 26 is mounted on a piston or at least operatively engaged with a piston 32. This piston is disposed in a cylinder 33, which is provided with a small opening 34 in the bottom 35, so that air or any fluid or other matter disposed in the cylinder below the piston and above the bottom 35 is being checked by such opening 34. The opening 34 is controlled by the washer or disc valve 36, turnably mounted on the screw 37. This washer is illustrated in detail in Fig. 2 of the drawing, showing the perforation or hole 38 and the groove 39, the groove 39 gradually decreasing in size and depth from a point near the hole 38 until it disappears from the surface of the disc 36 at 40. Such gradually sized groove serves to form ad-

justable means for the passage through the bottom 35 of the cylinder 33, as will easily be understood, since a setting of the washer or disc 36 so as to bring the groove 39 in front of the opening 34 in the bottom 35 in such a manner that the shallow termination of the groove will only allow a very small passage through the opening can easily be accomplished. By controlling the passage 10 through the opening 34 in the bottom 35 in this manner, the movement of the piston 32 within the cylinder can easily be controlled to such an extent that the piston can be made to move very slowly, thereby controlling the periods of the flashing produced by the device, as will be more fully explained hereafter.

The block or member 26, as part of the piston during the operation of the device, to 20 be influenced by the magnetic force from the coil 3 through the core 4, is provided with a circumferential groove 41 to engage the end of the lever 42. The lever 42 has preferably the same basic point around 25 which to swing as the lever 10, which, in the drawing is indicated by the pin 43, provided on the base 9. A spring 44 is engaging both levers, in the drawing such engaging being indicated at 45 and 46. Normally, such engaging is arranged so that the spring becomes located with its longitudinal center-line sidewise of the common swinging point 30 43. Such arrangement naturally produces the effect that an upward movement of the piston and thereby a swinging of the arm 42 in such a direction brings the engaging point 46 to a position so that the center-line of the spring 44 becomes located on the opposite side of the common swinging point 43, as 40 will easily be understood. As soon as the tension of the spring is so transferred to the opposite side from the common swinging point 43 of the two arms 42 and 10, the contact-arm 10 becomes subject to a tension 45 which has a tendency of swinging the contact arm 10 in an upwardly direction to come to rest against the plate or member 49. Such a movement and action is normally produced rather quickly, thereby quickly breaking 50 the contact between the two contact points 11 and 12. A breaking of this contact naturally means an interruption of the circuit through the coil, that being the operating 55 circuit of the device.

As long as an electric current is passing through the coil 3, the core 4 is being magnetized for drawing the block 24 as well as for drawing the block or member 26, therefore, an interruption in the operating 60 circuit through the coil means an interruption of such drawing of the blocks or members 24 and 23.

The moment the operating circuit becomes interrupted, the member 26 is free to descend

by the influence of its own weight, retarded in such descending movement by the controlling mechanism on the bottom of the cylinder 33. On reaching the lowermost position, in which the member 26 and piston 70 32 are illustrated, the spring 44 becomes naturally again located on the same side of the swinging point 43, thereby drawing the contact arm 10 to the same position in which it is illustrated and closing the operating 75 circuit as first described.

This operation is automatically repeated, a closed operating circuit causing the breaking of the derived circuit between the contact points 17 and 18 and also causing the 80 interrupting of the operating circuit, while the interrupting of the operating circuit means the releasing of the hammer 31 and thereby the closing of the derived circuit at 17 and 18 producing by its own interruption 85 also the closing of its own circuit again by the falling or moving of the member or piston 32, as will easily be understood.

Providing different engaging means for 90 the spring 44 on the arm 10 as well as on the arm 42 naturally allows an adjustment to such an extent that a short upward movement may be sufficient to operate the arm through the spring for interruption of the operating circuit while also allowing a 95 lengthening of such a movement, as will easily be understood.

We prefer to provide screw holes or similar means 47 in the arm 42, and similar 100 means 48 in the arm 10. Instead of securing the spring 44 to the arm 42 at the point indicated at 46, it will then be secured at a point to the left or to the right of the point 46 in one of the screw holes 47. Such changing of the spring towards the end of the operating arm 42 naturally brings the normal location of the spring practically across the supporting point 43 of the operating arm 42 so that a short movement upwards brings 110 the spring to the opposite side of the center swinging point 43 thereby naturally causing a snapping of the contact arm 10 towards the stop 49 for disengaging and interrupting the contact between the points 11 and 12. A change of the spring in the opposite direction, that is towards the supporting point 43, naturally requires a longer movement of the piston 32 and member 41 before the spring will be in a position to pull 115 the contact arm 10 to cause an interruption of the contact between the points 11 and 12, as will easily be understood. A changing of the opposite spring-end with relation to the point 45 on the contact arm 10 has similar effects, as will easily be understood.

Only one derived circuit is illustrated in the drawing, but it will easily be understood that any number of such derived circuits can be provided which can all be operated by

the hammer 31 as long as the hammer is made of such a size to reach over such a number of contacts 16 in such derived circuits as will easily be understood without further illustration or explanation.

Having thus described our invention, we claim:

1. In an electric flashing device, a coil disposed under the influence of an electric current in an operating circuit, a derived circuit embodying a spring contact normally closed when the operating circuit is closed, a hammer controlled by the operating circuit for opening the spring contact for interrupting the derived circuit, and a contact in the operating circuit under the influence of the coil for interrupting the operating circuit to close the derived circuit.
2. In an electric flashing device, a coil disposed under the influence of an electric current in an operating circuit for forming a magnetic field, a weighted member disposed under the influence of the magnetic field, an operating arm engaged with the weighted member, a contact arm disposed in the operating circuit, the operating and contact arms having the same point of support around which to swing, a spring disposed sidewise of the common support of the two arms engaging the operating arm with the contact arm so as to hold the contact arm in closed position under the tension of the spring when the operating arm is in the lowermost position while adapted to interrupt such contact when the operating arm is in a lifted position, and a derived circuit having means adapted to close the derived circuit on the interrupting of the operating circuit.
3. In an electric flashing device, a coil disposed under the influence of an electric current in an operating circuit for forming a magnetic field, a contact, a weighted member disposed to be influenced by the magnetic field, means for timing the movement of the weighted member, means for timing the commencing and ending of the movements and operations of the contact, and a derived circuit having means adapted to close the derived circuit on the interrupting of the operating circuit.
4. In an electric flashing device, a coil disposed under the influence of an electric current in an operating circuit for forming

a magnetic field, a contact, a weighted member disposed to be influenced by the magnetic field, means for timing the movement of the weighted member, means for timing the commencing and ending of the operation of the contact, a circuit independent of the first-named circuit of the magnetic field including a spring contact normally in closed position on interrupting of the first-named contact and operating circuit, and means disposed under the influence of the magnetic field for compressing the spring contact for breaking the contact and thereby by the second-named circuit.

5. In an electric flashing device, an operating circuit, a coil disposed in the circuit for forming a magnetic field, a contact disposed in the circuit, means for operating the contact under influence of the magnetic field, means for timing the operating means of the contact normally closed on the interrupting of the first-named contact and operating circuit, a second circuit including a contact, and means for disengaging the contact in the second-named circuit under the influence of the magnetic field formed by the first-named circuit.

6. In an electric flashing device, an operating circuit, a coil disposed in the circuit for forming a magnetic field, a contact disposed in the circuit, a weighted member disposed below the coil under the influence of the magnetic field, means for timing the movement of the weighted member when under the influence of the magnetic field and when free from such influence, means for timing the commencing and ending of the movement of the contact, a second circuit, a spring contact disposed in the second-named circuit above the coil and normally in closed position, and a pivotally supported arm disposed above the coil and under influence of the said coil and so disposed as to disengage the spring contact when under such magnetic influence by compressing such spring contact.

In testimony that we claim the foregoing as our invention we have signed our names in the presence of two subscribing witnesses.
